UNITED STATES PATENT OFFICE.

CHARLES L. PIERCE, JR., OF PITTSBURGH, PENNSYLVANIA.

INSULATOR SUPPORT.

Application filed March 11, 1920. Serial No. 365,002.

This invention relates to insulator supports and has for an object to produce such a support, which is simple and cheap to manufacture and is rigid and durable and at the same time light in weight.

A further object is to produce an insulator support member which may be pressed from sheet metal such as sheet steel.

These and other objects which will be made more apparent throughout the further description of the invention are attained by means of a device embodying the features herein described and illustrated in the drawings accompanying and forming a part hereof.

In the drawings, Figure 1 is a side view, a portion being shown in longitudinal section, of a support member embodying my invention; Figure 2 is a view along the line 2—2 of Figure 1; and Figure 3 is an end view of the device shown in Figures 1 and 2.

As illustrated, the support member consists of a base 4 which may be formed of sheet metal and to which one or more insulator support brackets 5 may be secured. As shown, the base member is substantially channel shaped in cross section and may be formed from sheet metal. It is provided at a point intermediate its ends with a sheet metal mounting strap 6, pressed to conform to the surface contour of the base 4 and secured thereto by means of rivets 7, which extend through the strap and through the web portion of the channel shaped base. As shown, the strap is provided at each end with mounting slots 8 adapted to receive or be engaged by mounting elements such as bolts or screws.

The base illustrated is adapted to carry two insulator support brackets 5 and is provided at each end with tenon receiving apertures for the purpose of receiving tenons formed on the brackets and thereby rigidly securing the brackets in place as will hereinafter be described.

As shown, each bracket is an angle or L shaped bracket, formed of sheet steel, is substantially U shaped in cross-section at its base engaging end, and is tapered to a substantially circular cross-section at its insulator supporting end. The brackets are so mounted on the base that the axis of the insulator supporting portion of each bracket extends substantially parallel to the surface of the web of the base 4. As shown the in-

sulator supporting end of each bracket is provided with a wire helix 9 similar to the insulator supporting helix of my Patent 1,158,149 of Oct. 26, 1915.

The base engaging end of each bracket is provided with integrally formed mounting tenons 11 which are adapted to be inserted through the tenon receiving apertures formed in the base 4 and to be riveted over or upset for the purpose of rigidly securing the bracket to the base. These tenons are preferably formed at the time of cutting or shearing the sheet metal of which the bracket is formed and the tenon carrying edge is of such shape that it fits the adjacent portion of the base throughout its length when moved into abutting engagement with the base. With this arrangement the bracket is, in effect, seated against the base portion when the tenons are in place in the tenon receiving apertures. As shown three tenons are provided on each bracket, one being located adjacent each lower edge of the bracket and one being located at an intermediate point between the other tenons, or as shown, at the apex of the arched portion of the base engaging end of the bracket.

While I have shown each bracket formed so as to provide a U shaped section at the base engaging end thereof, it will be apparent that the bracket may be formed of any section which contributes to ease of manufacture and is also sufficiently rigid to withstand the strains to which such brackets are subjected. I, however, preferably employ the tapered structure primarily because the larger base engaging end insures a more rigid and more substantial connection between the bracket and the base 4, and the tapering of the bracket occasions a saving in material by so distributing the metal throughout the length of the bracket that it is capable of resisting without deflecting such strains as may be encountered. Where a bracket, such as illustrated, is utilized, a minimum amount of metal is employed since the base engaging portion of U shaped cross section is extremely rigid and provides an ample base engaging seat for the bracket, whereas the portions of the bracket having less cross sectional area and of a shape less capable of resisting distortion, are subjected to less strain than is encountered at the base portion of the bracket. In other words, the area of the cross section and the

shape of the bracket is varied throughout the length of the bracket to take care of the stresses usually encountered.

Each bracket shown is so located on the base 4 that the arched portion of the U shaped section is on the upper side of the bracket thereby avoiding the formation of water collecting recesses and more or less protecting the mounting tenons from weather conditions. In addition the downwardly projecting parallel flanges of the U shaped portion materially stiffen the portion of the bracket subjected to the greatest cross bending stresses occasioned by the weight of the insulator and the wires or cables supported by it.

While I have illustrated and described but one embodiment of my invention it will be apparent to those skilled in the art that 20 various changes, modifications, additions and omissions may be made in the apparatus

illustrated, without departing from the spirit and scope of my invention as set forth by the appended claim.

What I claim is:

A fixture comprising a substantially channel shaped pressed metal base having tenon receiving apertures formed therein, in combination with an L-shaped insulator supporting arm pressed from sheet metal and having a substantially U-shaped edge abutting against said base, and tapered from said U-shaped edge to a substantially circular section at the outer end thereof, tenons integrally formed with said arm, projecting 35 from said U-shaped edge through the tenon receiving apertures of said base and riveted over to rigidly secure the arm to the base.

In testimony whereof, I have hereunto subscribed my name this 9th day of March, 40 1920.

CHARLES L. PEIRCE, JR.
